UNITED STATES PATENT OFFICE

147,377

DESIGN FOR A CHAISE LONGUE

Andrew Roth, Philadelphia, Pa., assignor to Bunting Glider Company, Philadelphia, Pa., a corporation of Pennsylvania

Application April 27, 1946, Serial No. 129,058

Term of patent 14 years

(Cl. D15—11)

To all whom it may concern:

Be it known that I, Andrew Roth, a citizen of the United States and a resident of Philadelphia, county of Philadelphia, State of Pennsylvania, have invented a new, original, and ornamental Design for a Chaise Longue, of which the following is a specification, reference being had to the accompanying drawing, forming a part thereof, wherein the figure is a perspective view of a chaise longue showing my new design.

I claim:

The ornamental design for a chaise longue, as shown.

ANDREW ROTH.
